UNITED STATES PATENT OFFICE.

ISAAC KENDRICK, OF PHILADELPHIA, PENNSYLVANIA.

GAS-BURNER.

SPECIFICATION forming part of Letters Patent No. 325,747, dated September 8, 1885.

Application filed August 7, 1884. (No model.)

To all whom it may concern:

Be it known that I, ISAAC KENDRICK, of Philadelphia, in the county of Philadelphia and State of Pennsylvania, have invented a 5 new and valuable Improvement in Apparatus for Burning Gas for Illuminating Purposes; and I do hereby declare that the following is a full, clear, and exact description of the construction and operation of the same, reference 10 being had to the annexed drawing, making a part of this specification, and to the letters and figures of reference marked thereon.

The figure of the drawing is a vertical sectional view of my device.

15 The object of this invention is to secure more perfect combustion, greater economy, and higher illuminating power from the consumption of a given quantity of gas than heretofore attained. To this end I employ, in 20 connection with a primary light-giving burner, a second or auxiliary heating-burner, and means for supplying heated gas to the primary burner, means for supplying gas and air to the auxiliary or heating burner, means 25 for creating and heating an upward current of air and directing the same to the inner surface of the flame of the primary or light-giving burner, means for outwardly and upwardly deflecting the flame and products of 30 combustion of the auxiliary or heating burner, and means for supplying and directing a current of air to the outer surface of the flame of the primary or light-giving burner at the point of ignition.

35 The invention consists in the construction and novel arrangement of devices, as will be hereinafter more fully set forth and claimed.

In the accompanying drawings, illustrating the devices usually employed in order to carry 40 my invention into effect, the letter A designates a chambered gas-light burner, which is preferably of annular form in cross-section, having a central opening, B, for the passage of air to the inner surface of the flame of this 45 burner, the gas passing to the burner by the pipe or pipes F.

C designates the interior auxiliary non-luminous or heating burner tube, located within the opening B of the main burner and extending upward to the level of or nearly to the 50 level of the jets of said main burner. This

heating-tube C is, at its lower end, provided with the jet-inlet e and with air-inlets d. An inverted-cone-shaped or cup-shaped deflector, D, preferably made of porcelain, is located 55 upon a stem or support, z, above the heater-tube C, its lower end or apex being at or near the center of the annular series of jets b of the main burner. This deflector, made capable of resisting injury from high heat, is designed to direct the flame and products of combustion of the non-luminous burner emitted at the upper end of the burner-tube C outward and upward around said deflector, and, becoming highly heated, to add to the 60 brilliancy of the flame of the main burner.

G represents the glass protector which surrounds the main-burner flame and guards it from lateral currents of air.

H indicates the gas-cock which regulates 70 the supply of gas to the main burner and to the heating-burner tube. Air-inlets e are provided to admit air to the opening or throat B of the main burner.

The operation is as follows: On opening the 75 gas-supply cock the gas issues through the jet perforations or nipples b of the primary or light-giving burner A, when it is ignited. Around the lower portion of the flame, and extending downward below the level of the 80 jets b, is the outer draft-collar, E, whereby air is supplied to the exterior of the main flame. At the same time gas is supplied to the interior of the auxiliary or heating burner tube C through the jet or jets e, and air is drawn 85 into said tube through the inlets d, and together the gas and air issue in a mixed condition from the upper end of the tube C, when it is ignited and burned as a heating-gas. The

heating-flame thus produced is, by means 90 of the deflector D, directed upward and outward around said deflector, heating it highly, and thereby adding greatly to the brilliancy of the main-burner flame. Air drawn upward through the burner-passage B by 95 the action of the interior heating-burner is highly heated, and in this condition is, by the deflector D, directed outward and upward and brought into close contact with the inner surface of the flame of the main burner. In 100 this manner it is designed to supply the air in proper condition to furnish oxygen to the

main light-giving flame to secure economy in the use of gas and to produce a high illuminating power in the main-burner flame.

By means of the interior heating-burner I am enabled to dispense with the ordinary tall chimney or draft-flue, because this burner creates a sufficiently strong upward draft of air, and at the same time heats it. The operation of this auxiliary burner is automatic or self-regulating. When the full pressure of gas is turned on at the light-burner, a correspondingly-strong draft of air is maintained by the interior or heating burner, and when the pressure of gas is diminished in the main burner the action of the auxiliary burner is also decreased, lessening the upward draft to the main flame.

I do not desire to limit this invention to the precise construction or arrangement of parts herein shown and described, as it is manifest that the same can be varied readily by persons skilled in the art without changing the principles of operation.

I am aware of the Patent No. 250,089, in which non-luminous gas is made use of, and the same passed through a heater which is composed of clay or similar material, and

highly heated by jets of the non-luminous gas, atmospheric air being forced through such heater and mingled with the non-luminous gas, issuing in one or more jet-flames against lime, magnesia, or similar material, to produce light by incandescence, and therefore do not claim such devices, broadly.

Having described this invention, what I claim, and desire to secure by Letters Patent, is—

In a gas-burner for illuminating purposes, the combination, with the annular gas-burner A, having a central opening or passage, B, of the auxiliary or heating burner tube C, its jet or jets c, and air-inlets d, the cone or cup shaped deflector D, arranged so as to have the flame pass on the outside thereof, the draft-collar E, and the regulating-valve H, substantially as specified.

In testimony that I claim the above I have hereunto subscribed my name in the presence of two witnesses.

ISAAC KENDRICK.
